LUMBER STICKER

Filed June 3, 1925

FIG. 2

FIG. 3

FIG. 4

INVENTOR.

BY
Frank A. Cutler,
ATTORNEY.

UNITED STATES PATENT OFFICE.

GEORGE F. ALEXANDER, OF WESTFIELD, MASSACHUSETTS.

LUMBER STICKER.

Application filed June 3, 1925. Serial No. 34,598.

My invention relates to improvements in devices commonly known as cross-sticks or stickers, for use in separating courses of boards, planks, squares, and lumber in other forms, when stacked or piled on skids or trucks, in kilns, or otherwise, for drying purposes, and consists essentially and generally or broadly of an element of appropriate size in cross section and length, having top and bottom sides spaced apart to permit of the free circulation of air laterally through such element, all as hereinafter more fully set forth.

Heretofore lumber stickers have been of such a character that no passage of air laterally through them has been possible, with the result that lumber separated thereby was subjected to crosswise instead of lengthwise currents of air. In consequence of this lumber thus separated was unevenly dried and caused to warp. The primary object of my invention is, therefore, to provide stickers that permit the air, which may or may not be heated or heated and rendered humid, to pass lengthwise of the lumber separated by such stickers, the air thus taking the direction of the sap in the tree from which the lumber is cut, and, therefore, what may be said to be the natural direction. The warping incident to the old method is thus eliminated, and the lumber caused to be dried evenly, and to be flat and straight at the end of the drying process.

A further object of my invention is to produce a sticker which is comparatively light in weight, and at the same time strong and durable, and one which can be readily manufactured at a comparatively low cost.

With these stickers lumber can be piled flat, edgewise, or vertically as may be desired, or depending on the nature of the drying element employed, or the character of the mechanical means used, or both. In short, my sticker is adapted to be applied in the loading, stacking, or piling of lumber in its various forms in any manner in which the old type of sticker is adapted to be used.

As is well known, stakes are frequently or usually employed to confine the lumber in piles, and hold the wooden cross-sticks in place, and it is understood that these and

any other devices, commonly used for keeping said cross-sticks in place in the load or pile, may be used in connection with my sticker.

55

Other objects and advantages will appear in the course of the following description.

I attain the objects and secure the advantages of my invention by the means illustrated in the accompanying drawings, in which—

60

Figure 1 is a side elevation of a sticker which embodies a practical form of my invention, a portion intermediate of the ends of the same being broken out; Fig. 2, a cross section through said sticker; Fig. 3, a longitudinal, vertical section through an end portion of said sticker, and, Fig. 4, a side elevation of a pile of boards the courses of which are separated by my stickers.

65

Similar reference characters designate similar parts throughout the several views.

In Fig. 4 a pile of boards 1 is represented, with stickers between the courses thereof. The boards might be piled with the longitudinal edges of one board respectively resting on a longitudinal edge of the board below and supporting the board above by a longitudinal edge thereof, or they might be arranged on end or vertically, in either of which events it would be necessary to provide suitable supporting means for these stickers, just as it is in the case of stickers of the old type.

70

The sticker, in the form as illustrated in connection herewith, comprises upper and under sides 2—2 consisting of strips of sheet-metal having their end portions bent into contiguity to produce the ends of the sticker, and a separator 3 consisting of a strip of sheet-metal bent into a generally zigzag shape, as hereinafter described, together with vertical end flanges 4, horizontal end flanges 5 and 6, and horizontal intermediate flanges 7 and 8. The separator 3 not only separates or holds apart the top and bottom sides 2, but also supports said top side and the load thereon, and assists in securing the said sides together, or in producing a strong and comparatively rigid structure.

85

Each end of the sticker consists of end portions of the top- and bottom-side strips 2 bent at right-angles to the major portions of

90

95

100

such strips, and fastened together by a pair of the flanges 4, one of such end portions, as 9, being bent downwardly (or upwardly), and the other of such end portions, as 10, being bent upwardly (or downwardly) outside of the other. The flanges 4 project from the vertical edges of the outer end pieces 10 to engage the end pieces 9. Each flange 4 extends over the adjacent edge of the contiguous end piece 9, and inwardly onto the inner face of said last-named end piece. Thus it is seen that the end pieces 9 and 10, at each end of the sticker, are securely fastened together at their vertical edges.

15 The separator strip is bent to form alternately arranged, top and bottom, horizontal, supporting parts 11—11 connected by oblique parts. The parts 11 are contiguous with the inner surfaces of the upper- and 20 under-side strips 2, and are securely attached to said strips by means of the flanges 6 and 7. The flanges 7 are arranged in pairs and extend from opposite longitudinal edges of the top- and bottom-side strips 2, and said flanges in each pair are bent over the lateral edges of one of the supporting parts 10 and inwardly against the inner surface of such part. The flanges 8 are also arranged in pairs and extend 25 from opposite longitudinal edges of the upper- and under-side strips 2, and said flanges are bent inwardly against the inner surfaces of said strips, between the supporting parts 10, and thus assist in holding 30 the separator 3 in place and stiffening the structure. The pairs of flanges 8 alternate with the pairs of flanges 7. There is a pair of flanges 5 at each end of the sticker, and these flanges are similar to the flanges 8, 35 except that said first-named flanges are shorter than the others, and those in the two pairs extend from the adjacent end pieces 9, respectively above and below the upper and lower ends of the adjacent 40 flanges 4, to the supports 11 which are next adjacent to said end pieces. The supports 11, at the ends of the separator 3, terminate 45 at the end pieces 10, after respectively passing under and over the lower and upper ends of the flanges 4 and end pieces 9. Each flange 6, at each end of the sticker, is shorter than any flange 7, and is in the 50 same vertical plane with the adjacent flange 4, the abutting edges of said flanges 6 and 4 being cut at any angle of 45 degrees.

55 The separator 3 forms a truss for the top and bottom sides 2, which truss maintains said sides in spaced and parallel relationship, and said separator and the fastening means, comprising the flanges 5, 6, 7, and 8, make the structure strong and durable, comparatively rigid, and capable of carrying or supporting the weight of the lumber piled on the sticker.

55 The space between the top and bottom

sides 2 and the ends of each sticker is open, except, of course, where the oblique parts of the separator 3 cut edgewise across the same, consequently air can pass freely through the stickers lengthwise of the boards 70 1, instead of, as heretofore, only between said stickers.

More or less change in the shape, size, construction, and arrangement of some or all of the parts of this device may be made 75 without departing from the spirit of my invention or exceeding the scope of what is claimed.

What I claim as my invention, and desire to secure by Letters Patent, is—

1. A lumber sticker comprising top and bottom members, and a separator between which permits air to pass laterally through the sticker, said top and bottom members being provided with flanges to engage said separator and secure the parts together.

2. A lumber sticker comprising top and bottom sides, and a separator bent to form alternately arranged upper and under supports which are in contact with said top and bottom sides, the latter being provided with flanges to engage the contacting parts of said supports.

3. A lumber sticker comprising top and bottom sides, a separator bent to form alternately arranged upper and under supports which are in contact with said top and bottom sides, the latter being provided with flanges to engage the contacting parts of said supports, and means against said sides and between said supports to assist in retaining the latter in spaced relationship.

4. A lumber sticker comprising top and bottom sides, and a separator bent to form alternately arranged upper and under supports which contact with said top and bottom sides, the latter being provided with flanges to engage the contacting parts of said supports, and with flanges which are bent inwardly between said supports.

5. A lumber sticker comprising top and bottom sides having end portions bent into contiguity and integral means to secure such bent end portions together, a separator having a generally zigzag form and introduced between said top and bottom sides, and means to secure said sides and separator together.

6. A lumber sticker comprising top and bottom sides having their end portions bent into contiguity, one of such bent portions at each end of the sticker being provided with flanges to embrace the vertical edge portions of the other of such bent portions at such end of the sticker, a separator having a generally zigzag form and introduced between said top and bottom sides, and means to secure said top and bottom sides and said separator together.

7. A lumber sticker comprising top and

bottom sides having end portions bent into and under supports which are in contact contiguity, one of such bent portions at each end of the sticker being provided with flanges to embrace the vertical edge portions of the other of such bent portions at such end of the sticker, and a separator bent to form alternately arranged upper

and under supports which are in contact with said top and bottom sides, the latter being provided with flanges to engage the contacting parts of said supports, and with flanges which are bent inwardly between said supports.

GEORGE F. ALEXANDER.
